UNITED STATES PATENT OFFICE.

EMERY R. WILEMAN, WINFRED H. WILEMAN, AND JUDSON C. CLEMENT, OF WOODRUFF, KANSAS.

COMBINATION LIFTING-JACK AND WIRE-STRETCHER.

964,594.

Specification of Letters Patent. Patented July 19, 1910.

Application filed September 28, 1909. Serial No. 519,920.

To all whom it may concern:

Be it known that we, EMERY R. WILEMAN, WINFRED H. WILEMAN, and JUDSON C. CLEMENT, citizens of the United States, 5 residing at Woodruff, in the county of Phillips and State of Kansas, have invented certain new and useful Improvements in Combination Lifting-Jacks and Wire-Stretchers; and we do hereby declare the following to be a full, clear, and exact description of the invention, such as will enable others skilled in the art to which it appertains to make and use the same.

Our invention relates to new and useful 15 improvements in combination lifting jacks and wire stretchers and our object is to provide means for raising different articles when desired and more especially the axles of a vehicle when it is desired to remove the 20 wheel therefrom.

A further object is to provide means in connection with the lifting device, whereby the same may be used for stretching wires or the like and a further object is to provide 25 an extension for the lifting device whereby the same may be used for raising objects from a point adjacent the base of the lifting device.

Other objects and advantages will be hereinafter referred to and more particularly 30 pointed out in the claims.

In the accompanying drawings forming part of this application, Figure 1 is a side elevation of the combination lifting jack and wire stretcher. Fig. 2 is a sectional view as seen on line 2—2, Fig. 1. Fig. 3 is a perspective view of a slightly modified form of lifting jack, and, Fig. 4 is a detail view partly in section of the upper portion of that 40 form of lifting jack shown in Fig. 3.

Referring to the drawings in which similar reference numerals designate corresponding parts throughout the several views, 1 indicates a base, which may be constructed 45 in any preferred form, extending upwardly from which is a tube 2, into which is introduced a shank 3, the upper end of said shank being provided with a head 4, which is adapted to be introduced below an object when said object is to be elevated.

Attached to the base 1 is a standard 5, which standard is formed by bending a piece of metal upon itself and securing the two sections thereof to the base, thereby 55 forming a slot 6 the full length, the lower

end of the standard having angular extensions 7, through which and the base 1 are introduced bolts 8 and by means of which the standard is attached to the base.

Fixed to the upper end of the tube 2 and 60 extending into the slot 6 of the standard 5, is a head 9, while pivotally attached to said head, is a ring 10, through which the shank 3 extends, the axis of the opening 11 through said ring being at an angle to the axis of the 65 shank 3 and of greater diameter than said shank, whereby when the ring is resting in a horizontal position, the upper end of the opening will engage the shank, while the lower edge of the wall of the opening will 70 engage the shank diametrically opposite the point of engagement as first described and at the lower end of the opening, said ring exerting a binding action on said shank when the ring is resting in a horizontal position, said ring serving to hold the shank 75 against casually descending when resting in a horizontal position.

Pivotedly mounted in the slot 6 and adjacent the upper end of the standard is a 80 lever 11^a, to the inner end of which is pivotally attached a link 12, while to the upper end of the link is attached a ring 13 similar to the ring 10, the walls of the opening 14 in said ring 13 being arranged similar to the opening 11 in the ring 10, whereby the ends of the opening 14 will grip the surfaces of the shank and move said shank upwardly, when downward pressure is applied to the outer end of the lever. 90

In operating the device as a lifting jack, the head 4 is positioned below an object and the shank raised until the head engages the object, the two rings, in view of the angle of the openings therethrough, permitting the shank to freely move upwardly. As soon as the head is seated against an object, downward pressure is applied to the outer end of the lever 11^a, which would cause the ring 13, in view of the angle of the opening therethrough, to engage the shank and move said shank upwardly, while the ring 10 will bind against the shank 3 as soon as pressure is released from the lever 11^a and hold said shank against descending. The outer end 100 of the lever is then thrown upwardly its full stroke, which will lower the ring 13 on the standard and obtain a new purchase thereon, so that when the lever is again lowered, the shank will be further elevated and this op- 105 110

eration continued until the object is raised to the proper height. When it is desired to lower the shank into the tube, the lever 11^a is thrown upwardly to bring the wall of the opening 14 substantially parallel with the shank 3 and the ring 10 is similarly positioned through the medium of a cam 13, said cam being pivotally attached to the head 9 and in position to be swung into engagement with the lower face of the ring 10, whereby said ring will be swung on its pivot and the wall of the opening 11 brought substantially in alignment with the shank 3 and when the rings are so positioned, the shank may be freely moved downwardly.

When the device is to be used for stretching wire, or similar objects, a chain or cable 16 is attached to a staple 17 on the lower end of the shank, said chain being used for anchoring the lifting device, while to the upper or closed end of the standard is secured a stretching chain 18 and by anchoring the lifting jack through the medium of the chain 16, and attaching the chain 18 to a strand of wire, or a section of woven wire, said wire may be readily stretched by operating the lever 11^a.

In Figs. 3 and 4 we have shown a slightly modified form of lifting jack and have shown attached thereto an extension 19, the upper end of which is provided with a hook 20, the free end of which is adapted to enter a socket 21 in the upper end of the shank 3, while the lower end of the extension is provided with a fork 22, which rests against the tube 2 and holds the extension parallel with the tube. The object of providing the extension, is to enable the jack to be used for raising objects from a point near the base of the jack, said extension having a foot piece 23 at its lower end, which is adapted to extend below and engage the object to be lifted. In this construction, the head 9 is provided with a laterally extending arm 24, the outer end of which is extended upwardly and provided with a pin 25, with which engages the terminal 26 of a locking ring 27, the opening 28 in said ring being constructed similar to the openings in the rings 10 and 13, the terminal 26 being provided with an oblong slot 29, through which the pin 25 extends. By arranging the ring 27 in this manner, the shank will be securely held in its elevated position and when it is desired to lower the shank, the ring is lifted through the medium of a finger piece 30, the provision of the slot 29 permitting the ring to be swung upwardly. This form of device may also be used for stretching wire, etc, by providing the chain attachment as shown in Fig. 1, the operation of the two forms of jack being the same.

By this construction, it will be seen that we have provided a very cheap and durable 65 form of lifting jack and one that can be readily converted into a wire stretcher and it will further be seen that by using the extensions, the jack may be employed for lifting objects of various heights from the base 70 of the jack.

What we claim is:

1. In a lifting jack, and stretcher, the combination with a base, a tube on said base and a standard connected to said base; of a 75 shank telescoped in said tube, a head connecting the upper end of the tube to said standard, a ring carried by said head, said ring having an opening through which the shank extends, the wall of said opening being at an angle to the trend of the shank, an additional ring surrounding said shank and above the first mentioned ring, a lever pivotally attached to said standard and a link connecting said lever and the last referred to ring. 80

2. A device of the character described, comprising the combination with a base, a tube and a standard rigidly secured thereon; of a shank in said tube, bracing means between said tube and standard, ring members encompassing said shank, one above the other and having openings therein disposed at an angle, one of said ring members being carried by portions of said bracing means, 90 a lever pivotally secured to said standard and a link secured to the inner end of said lever, the opposite end of said link being pivotally secured to said other ring member, whereby when said lever is pressed downwardly, said shank will be elevated and prevented from moving to its normal position. 100

3. In a device of the character described, the combination of a base, a standard and a tube rigidly secured to and extending upwardly from said base, a shank in said tube, bracing means between said standard and tube, a pair of rings encompassing said shank, one above the other and having inclined openings therein, one of said rings 110 being pivotally secured to said bracing means, an operating lever fulcrumed on said standard, a link secured at its upper end to the other of said rings and at its lower end to said lever and means on said shank for 115 engaging and raising an object. 105

In testimony whereof we have signed our names to this specification in the presence of two subscribing witnesses.
